UNITED STATES PATENT OFFICE.

EDWIN M. BURT, OF HARVARD, ILLINOIS.

GATE.

SPECIFICATION forming part of Letters Patent No. 230,609, dated August 3, 1880.

Application filed May 17, 1880. (No model.)

To all whom it may concern:

Be it known that I, EDWIN M. BURT, a citizen of the United States, residing at Harvard, in the county of McHenry and State of Illinois, have invented a new and Improved Gate; and I do hereby declare the following to be a full, clear, and exact description thereof, which will enable others skilled in the art to which my invention appertains to make and use it, reference being had to the accompanying drawings, forming part of this specification, wherein—

Figure 1 is a front elevation of the gate, showing my improvements. Fig. 2 is a similar view, showing the end of the gate raised. Fig. 3 is a perspective view of the clamp by which the swinging end of the gate is adjusted vertically; and Fig. 4 is a plan view of the gate at the hinged end, showing the saddle for the guide-rods.

Similar letters of reference denote the same parts in the several figures of the drawings.

My invention has for its object to improve the operation of farm-gates, by which they can be swung clear of snow and other obstructions, their swinging or latch end adjusted to compensate for the sagging of the post or the gate itself, and which can be so operated as to separate stock—that is to say, to permit the passage of sheep and other small animals and prevent the passage of cattle and horses.

To this end the invention consists in forming the gate with flexible joints, and combining with it a clamp guided from the top hinge or hinged end of the gate, to move vertically on the swinging end and hold it at any desired elevation.

In the accompanying drawings, A represents the gate hinged to the center of a post, B, to swing against or past a post, C, in both directions, and constructed in the usual manner of farm-gates, excepting that its joints are made flexible by pivot-bolts *d*, or other suitable devices. This construction allows the front or swinging end of the gate to be moved freely up and down within certain limits without affecting its movement on the hinges.

E is the clamp, made of wood or metal, to partly embrace the vertical bars F at the latch end of the gate in such a manner as to slide

freely up and down. It is connected with the upper hinge on each side of the gate by means of rods or wires G G, the connections being made flexible in any manner to let the clamp rise and fall when necessary. As shown in the drawings, the rods are jointed about midway of their length and attached to ears projecting from opposite sides of the clamp; but this construction may, of course, be varied without departing from the invention.

When the latch end of the gate is raised, which may be readily done by hand, the clamp drops down upon the bars F until arrested by the guide or stop rods, which cause it to bind against the bars, and thus hold up the end of the gate, as shown in Fig. 2. In this position it forms an effectual barrier against the passage of large animals, while small animals can easily pass under it. Thus it affords a convenient means for separating stock.

To lower the end of the gate the clamp is lifted slightly, when the gate falls through the required distance by gravity. The adjustability of the clamp also permits the gate to be raised and swung over snow and other obstructions, and then swing back again to its place, and also adapts the gate to be held at any desired height to compensate for sagging.

As the gate can be raised a considerable distance above a central horizontal line, it is evident that it can also fall as far below such line when the clamp is lifted. Therefore it can be let down to the ground at any point upon either side of the post to prevent the wind from swinging it, to break the slats, strain the hinges, or otherwise injure the gate.

H is a saddle attached to the upright of the gate at the upper hinge to prevent the guide-rods from wearing into the upright, and also to afford means for fastening the wires, which in this case is effected by passing them through an eye, K, on the saddle, as shown in Fig. 4.

The clamp E may be corrugated or otherwise roughened on its inner surface to more effectually hold the gate at the desired point, although this is not absolutely necessary.

The gate-latch may be arranged in any convenient way, and may work through, over, or under the clamp; or the latter may be made in two parts, if preferred, and instead of guide

rods or wires, ropes, or cords may be used for holding the clamp.

Having thus described my invention, what I claim is—

1. The combination, with the flexible-jointed farm-gate, of the vertically-adjustable clamp, and its guide-rods, substantially as described, for the purpose specified.

2. The saddle H, connected to the rear upright of the gate, and combined with the clamp,

and the guide-rods, substantially as described, for the purpose specified.

In testimony of which invention I have hereunto set my hand this 20th day of April, A. D. 1880.

EDWIN M. BURT.
